STOCK FEEDING MEANS

Newman M. Marsilius, Trumbull, Conn., assignor
to The Productor Machine Company, Bridge-
port, Conn., a corporation of Connecticut

Application August 20, 1951, Serial No. 242,630

13 Claims. (Cl. 203—115)

1

This invention relates to new and useful improvements in stock feeding devices and has particular relation to an accurate stock feeding means especially adapted for attachment to a press.

An object of the invention is to provide a stock feeding means wherein stock feeding movement is brought about by movement of a machine part and wherein the stock feeding movement in the means is through a greater distance than the movement of the mentioned machine part.

Another object is to provide a stock feeding means having the characteristic stated and which is of simple, inexpensive and rugged construction whereby it is convenient to use and has a long useful life.

Other objects and advantages of the invention will become apparent from the consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claim.

In the drawings:

Fig. 1 is a top plan view showing the stock feeding means of the invention.

Fig. 2 is a side elevational view thereof, taken as looking from the lower side of Fig. 1 and showing the means of the invention in operative association with a die bed and punch holder of a press-mounted die set.

Fig. 3 is a bottom plan view of the improved stock feeding means.

Fig. 4 is a transverse sectional view taken as along the plane of the line 4—4 of Fig. 1 and looking in the direction of the arrows.

Fig. 5 is a similar view taken as along the plane of the line 5—5 of Fig. 1 and looking in the direction of the arrows; and

Fig. 6 is an end elevational view of the improved stock feeding means.

In the drawings, the stock feeding means 10 of the invention is shown as mounted on the die bed 11 of a press (not shown) for actuation by the punch holder 12 of the press. Means 10 comprises generally four main parts 13, 14, 15 and 16 mounting and mounted on a pair of bars 17 and 18. That is, the part 13 mounts said bars 17 and 18 in turn mounted on the die bed while the parts 14, 15 and 16 are mounted on said bars.

Part 13 (see Fig. 6) comprises a pair of side

2

members 19a and 19 integrally connected at their lower ends by a body 20 including a forward extension 21. The plate and its extension have countersunk holes 22 for the passage of securing screws 23 whereby the present stock feed means is attached to the die bed 11 (Fig. 1). Side members 19a and 19 have parallel holes 24 therethrough receiving the bars 17 and 18 whereby the part 13 is mounted. Set or lock screws 25 secure the part 13 in the desired position on the said bars 17 and 18.

Part 14, comprising a stock feeding slide, is slidable on the bars 17 and 18 rearwardly from and forwardly toward the part 13. This second part comprises end members 26 and 27 connected by an integral lower body portion 28 having a depending L-shaped portion 29 and spaced therefrom, a depending straight lug on spud 30. Members 26 and 27 have parallel openings 31 therethrough and receiving the bars 17 and 18 whereby the part 14 is slidably mounted on said bars.

A pair of upstanding ears 32 and 33 comprising integral portions of the members 26 and 27, respectively, have aligned openings 34 and 35 normal to the openings 31. Turnable in said openings about its own longitudinal axis is a shaft 36 which, between the ears 32 and 33, has a mounting device 37 secured thereon by screws 38. Device 37, see Fig. 2, partly embraces the shaft 36 and the latter has a flat side against which is disposed a plate or feed cam 39, held to the shaft by binding screws 40 passing through vertically extending slots therein as will be further explained when considering Fig. 5.

Adjusting screws 41, held in their adjusted positions by lock nuts 42, extend downwardly through portions of the device 37 and are so located that their lower ends engage spaced upper edge portions of the feed cam 39. On loosening of the screws 40 the screws 41 may be adjusted to move the feed cam downwardly and thus bring it nearer to a wear plate 43 comprising a portion of part 14 and also extending between the side members 26 and 27. Further, on loosening of screws 40 and adjusting upwardly of the screws 41, the said feed cam may be adjusted away from plate 43. After any adjustment the binding screws and the lock nuts are tightened. Feed cam 39 is adjusted with respect to plate 43 depending on the thickness of stock to be fed.

Part 14 also includes a plate 44 located at the rear side of said part and having its end portions secured against the upstanding ears 32 and 33 of said part by screws 45. Plate 44 constitutes an anchoring means through which passes a rod

46 at its forward end passing through a vertical slot in the feed cam 39 and receiving a nut 47. Rearwardly of plate 44 a coil spring 48 surrounds the rod 46 and bears at its respective ends against said plate and nuts 49 on the rod. By adjusting the nuts 49, the pressure exerted by the spring against the nuts and the plate 44 is varied and thus the pull on feed cam 39 regulated.

Slidably mounted on the bars 17 and 18 rearwardly of the part 14 is the part 15 (Fig. 5) comprising a motion imparting slide as well as a stock supporting and hold-down guide positioned at all times between the parts 14 and 16 at a medial point. The latter part comprises a pair of end members 50 and 51 integrally connected by a body 52 having a pair of depending oppositely facing L-shaped lugs 53 and 54. Parallel openings 55 through said members receive the bars 17 and 18 and thus the part 15 is mounted for sliding movement longitudinally of said bars.

Spaced upstanding ears 56 and 57, comprising portions of members 50 and 51, have aligned openings 58 and 59 normal to the bars 17 and 18 and rotatively receiving the end portions of a shaft 60 which is parallel with the shaft 39 of part 14. A wear plate 61 is fastened to body 52 by screws 62 and above said wear plate 61 but secured to the members 50 and 51 and thus movable with the wear plate, is a hold-down plate 63, the latter having its ends located in slots or recesses 64 in the opposed portions of said members 50 and 51.

The rearwardmost part 16 (see Fig. 4) comprising a holding part, also includes a pair of end members 65 and 66 integrally connected by a body 67 having a depending L-shaped lug 68 and a depending straight lug or spud 69. A wear plate or combined wear and clamping plate 70 is secured against the upper side of body 67 by screws 68. In this connection it is noted that the upper surfaces of plates 43, 61 and 70 are all in the same plane.

Upstanding ears 71 and 72 of members 65 and 66 have aligned openings 73, normal to the bars 17 and 18 and receiving the end portions of a shaft 74. On said shaft is a mounting device 75 (similar to the mounting device 37 of part 14) partly embracing the shaft and secured thereto by screws 76. Lying against a flat portion of shaft 74 between the ears 71 and 72 is a hold cam 77 comprising a plate and binding screws 78 passing through vertical slots 79 in said hold cam secure the latter to the shaft.

Adjusting screws 80 held in adjusted positions by lock nuts 81 cooperate with the binding screws 78 for adjustment of the hold cam 77 in the same manner as that described when considering feed cam 39 and the screws 40 and 41 of part 14. Across the rear of the part 16 is an anchoring plate 82 secured in place to upstanding ears 71 and 72 by screws 83 and this plate is for the purpose of plate 44 of part 14. Thus, a rod 84 passes through plate 82 and a vertical slot 85 in hold cam 77 and is secured by a nut 84a. At the rear side of plate 82 a coil spring 86 surrounds the rod and bears at its respective ends against the plate and a pair of nuts 87 and thus acting through the rod biases the cam plate.

An inverted L-shaped member 88 is secured to the rear edge of body 67, below the lower edge of plate 82, by screws 89 and has its upper longitudinal arm 90 provided with slots 91 extending longitudinally thereof and transverse with respect to bars 17 and 18. Guide rollers 92 are mounted on said arm 90 by screws 93 and serve to secure 75

the rollers in adjusted relation, closer to or further from one another, depending on the width of stock being fed, with the limits made possible by said slots.

5 In the completely assembled stock feed the parts 13 and 16 are fixed with respect to one another and to the other parts. Thus, part 13 is fixed to the bars 17 and 18 by the screws 25 while the part 16 is also secured to said bars by screws 95. Secured on the bars 17 and 18 at the rear of part 14 are collars 96 fastened in place by screws 97.

Upstanding ears 98 and 99 of the end members 19a and 19 of part 13 (see Fig. 6) have aligned openings 100 receiving the end portions of a shaft 101 extending normal to the said bars. Shaft 101 has an end portion 102 extending at the outer side of ear 99. A member 103 includes a relatively long arm 104, a shorter arm 105 and a connecting portion 106, the latter straddling ear 99 and the inner ends of said member 103 pivoted by the shaft 102 to which it is fixed by a screw 107.

The shaft 60 of part 15 mounts a cylindrical piece 108 integral with an upwardly and forwardly extending arm 109 pivotally connected at its forward end with the upper rear end of the arm 104 by a pivot pin 110. Thus arms 104 and 109 combine to form a toggle. A screw 111 may locate the shaft 60.

20 A laterally extending operating arm 112 includes a forward extension 113 provided with countersunk openings 114 for the passage of screws 115 securing said arm to the punch holder 12. At its laterally outer end, arm 112 includes an eye 116 through which extends a vertical rod 117 clamped in position by nuts 118 threaded thereon and tightened against the upper and lower sides of said eye.

40 Vertically adjustable on the rod 117 are upper and lower plates 119 and 120, respectively, keyed against rotation about the rod by pins 121 entering a vertical slot or groove 122 in the rod. Nuts 123 and 124 at the upper and lower sides of plate 119 are threaded to the rod 117 and are used for securing the plate in the desired adjusted position and nuts 125 and 126 at the upper and lower sides of plate 120 serve the same purpose for that plate.

Extending laterally from the short arm 105 of member 103 is a rigid pin 127 held in place by a screw 128. This pin extends between the plates 119 and 120 and is adapted to be actuated by them as the arm 112 is moved with the punch holder of a press as, for example, with the punch holder 12, to extend and collapse the toggle structure above described.

50 A rack 129 extending parallel with the rods 17 and 18 has its forward end portion located in the notch of the L-shaped lug or depending extension 29 of the part 14 and secured thereon and to said part by screws 130. The rear portion of this rack is aligned with the L-shaped depending lug 54 of the part 15 but is not secured thereto whereby there may be relative movement of part 15 and the rack.

55 A second rack 131 has its rear end portion located in the notch of the depending L-shaped lug 68 of the stationary part 16 and is secured thereto by screws 132. The rack 131 is aligned with the notch of the depending L-shaped lug 53 of part 15 but is not secured thereto whereby relative movement may take place between the rack and the part in a path parallel with the longitudinal axis of the rack.

Slidable part 15 carries a gear 133 rotatable

about a bushing 134 held in place by a stud 135 threaded into the body 52 of the said part. This gear is thus located between the inner overlapping end portions of the racks 129 and 131 and its teeth mesh with those of the two racks which are located at opposite sides of the gear. About the bushing 134 and the stud 135 and between the head of said stud and the underside of gear 133 is a large diameter member 136 between the free opposed ends of the inwardly directed arms of the L-shaped depending lugs 53 and 54 of part 15.

With the described construction, it will be understood that on sliding movement of motion imparting slide 15 on the bars 17 and 18 the gear meshing with the rack 134, secured to the stationary part 16, will be rotated and since the gear also meshes with the teeth of rack 129, rotation of the gear will feed or move the rack 129 longitudinally and thereby cause movement, along the bars 17 and 18, of the stock feeding slide or part 14. The relationship of the parts is such that for a given movement of part 15 the part 14 is moved twice as far. Thus, when the slideable part 15 is moved one inch, the slideable part 14 is moved two inches, etc. Consequently, the motion imparting slide 15 will always be disposed at a substantially medial point between the stock feeding slide 14 and the holding part 16, the increase or decrease in the distance of the motion imparting slide 15 from the feeding slide 14 at one side and holding part 16 at the other side being always equal. Thus the stock is always supported at a mid point between the point engaged by the hold cam 77 of the stationary holding part 16 and the point engaged by the feed cam 39 of the movable stock feeding slide 14. This relationship is clearly illustrated in Fig. 2. The advantage of this arrangement is that the stock is prevented from sagging or buckling between the hold cam 77 and the feed cam 39 by being supported at a mid point between these parts in any position of the feed slide 14. As the stroke of part 14 determines the amount of the stock feed, it will be clear that with the means of the invention, for a small stroke of the press, a considerable movement of stock will be obtained.

When setting up for operation, assuming that the parts are secured to the bed and punch holder of a die set and the latter is mounted in a press, the gates are brought to the lowest point. Then the top plate 119 is adjusted downwardly on the rod 117 until said plate touches the pin 127 and the plate is locked in this position by the nuts 123 and 124, with the slideable part 15 against the rearward stationary part 16.

Next, upward movement of the gate is started but prior to the full back stroke the bottom plate 120 is adjusted upwardly on the rod 117 for the proper stroke space between parts 15 and 16. This, in the embodiment disclosed, is one-half. Then, in the embodiment disclosed, is one-half and the stroke required in the slideable part 14 and now the collars 96 are set up against the slideable part 14 and locked. The feed cam plate 39 should be set at an angle of about twelve degrees for all strokes up to one thirty-second of an inch and less angle may be set for heavier stock.

Now the stock to be fed is threaded into the feeding means of the invention by passing the stock over shelf-like arm 90 and between the guide rollers 92, between the wear plate 70 and the hold cam 77, between the wear plate 61 and the hold-down plate 63, between the wear plate 43 and the feed cam 39, and thence forwardly between the upstanding portions 98 and 99 of the

end members 19a and 19 of part 13 and into the press.

Stock may move forwardly under the hold cam 77 but on an attempted retrogressive movement 51 of the stock member under said cam the latter bites against the stock clamping it against plate 70 and prevents such retrogressive movement. In somewhat like manner, the feed cam 39 functions. The feed cam may be carried rearwardly over the stock and the latter is held by cam 77. On forward movement of the feed cam with part 14, the feed cam 39 bites against the stock clamping it against plate 43 and as part 14 moves forward the stock is moved with it, being dragged under hold cam 77.

From the foregoing it will be seen that the stock being in place and the press open as the punch holder starts down or toward closed position arm 112 and with it the rod 117 and plates 20, 119 and 120 are moved downwardly. At this time, the toggle formed by the arms 104 and 109 is folded and feed slide or part 14 is in its forward position and part 15 is in a forward position. As the press closes, plate 119 engages pin 25 127 and presses the same downwardly straightening the described toggle structure and shifting part 15 rearwardly.

The gear 133 is now rotated by engagement with the teeth of rack 131 and operates through the teeth of rack 129 to draw part 14 rearwardly. Retrogressive movement of the stock is prevented by hold cam 77. Because of the gear and rack structure the movement of part 14 will be twice the movement of part 15. As the opening stroke of the press progresses, plate 120 engages the pin 127 raising it and thereby operating to fold the described toggle structure and move part 15 forwardly on the bars 17 and 18. As gear 133 is thus moved along the teeth of stationary rack 131, the gear is rotated and meshing with the teeth of rack 129, shifts the latter forwardly and thus moves the part 14 and the feed cam 39 forwardly. At this time the feed cam is engaging the stock and the latter is dragged forwardly a distance equal to the forward movement of part 14. Because of the gear and rack structure, the part 14 will be given a forward or stock feeding movement for a distance or length of stroke twice that imparted to part 15.

Thus, while the stock feeding means of the invention is of general application, it may find particular use for the feeding of stock to a press having a short stroke.

Having thus set forth the nature of my invention, what I claim is:

In a strip stock feeding means, a forward transverse stationary mounting part, a rearward transverse stationary holding part longitudinally spaced from said forward stationary part having a stock feeding passage defined at its lower side by a stock supporting wear surface, longitudinal guide means extending between said stationary parts, a stock feeding slide mounted 60 on said guide means for forward and rearward reciprocatory movement and having a stock feeding passage defined at its lower side by a stock supporting wear surface and longitudinally aligned with said passage of said rearward stationary part, a motion imparting slide mounted 65 on said guide means between said rearward stationary part and said feeding slide for forward and rearward reciprocatory movement and having a stock feeding passage defined at its lower side by a stock supporting wear surface and

longitudinally aligned with said passages of said rearward stationary part and said feeding slide, one-directional stock gripping means on said stationary part defining the upper side of its stock feeding passage adapted to permit forward movement and to restrain rearward movement of stock therethrough, one-directional stock gripping means on said feeding slide defining the upper side of its stock feeding passage adapted to grip stock and move it forwardly through the forward movement of said feeding slide and to move freely over said stock during the rearward movement of said feeding slide, stock hold-down means on said motion imparting slide defining the upper side of its stock feeding passage and adapted to move freely over said stock during both forward and rearward movements of said motion imparting slide, driving means to impart forward and rearward movement to said motion imparting slide, a horizontal longitudinally extending stationary rack fixed at its rearward end to said rearward stationary part, a horizontal longitudinally extending movable rack fixed at its forward end

15 10

5 to said feeding slide, said racks being parallel and in laterally spaced overlapping relation at their inner ends, and a gear carried by and rotatable on said motion imparting slide and meshing with each of said racks for rolling engagement along said stationary rack and for imparting movement to said movable rack and thus to said feeding slide, whereby as said motion imparting slide is moved forwardly and rearwardly a given distance said feeding slide is moved forwardly and rearwardly twice such distance.
